UNITED STATES PATENT OFFICE.

HENRY B. SARGENT, OF NEW HAVEN, CONNECTICUT, ASSIGNOR TO THE SARGENT & COMPANY, OF SAME PLACE.

DESIGN FOR A LEVER FOR SASH-FASTENERS.

SPECIFICATION forming part of Design No. 33,739, dated December 18, 1900.

Application filed November 22, 1900. Serial No. 37,402. Term of patent 14 years.

To all whom it may concern:

Be it known that I, HENRY B. SARGENT, of the city and county of New Haven, in the State of Connecticut, have invented a new Design 5 for Levers for Sash-Fasteners, of which the following is a full, clear, and exact description, when taken in connection with the drawings, which form a part thereof, and in which—

Figure 1 represents a top view of a lever embodying my design; Figs. 2 and 3, rear and front views, respectively; and Fig. 4, a bottom view of the same.

In all the figures similar letters of reference represent like parts.

15 This invention relates to a design for a lever for sash-fasteners; and it consists in the configuration hereinafter described, and shown in the drawings above referred to.

The lever consists of a substantially flat 20 parti-circular plate A, which is provided at one side with a vertical thumb-piece B. At the center of the arc forming the periphery of the plate is a vertical perforation a. The

sides C of the lever are convex and inclined outwardly and downwardly, except on the 25 front c, where the side is substantially vertical.

On the under side of the plate A is a curved slot D, one end of which terminates at the straight side c, where, as shown at d, it is flared 30 and upwardly inclined.

Having now described my design, what I claim, and desire to secure by Letters Patent, is—

The design for a lever for sash-fasteners, 35 as herein shown and described.

In witness whereof I have hereunto set my hand, in the presence of two subscribing witnesses, at New Haven, in the county of New Haven and State of Connecticut, this 15th day 40 of November, 1900.

HENRY B. SARGENT.
